UNITED STATES PATENT OFFICE.

GEORGE D. BANCROFT, OF BOSTON, MASSACHUSETTS.

ELECTRIC GAS-LIGHTING APPARATUS.

SPECIFICATION forming part of Letters Patent No. 247,737, dated October 4, 1881.

Application filed August 1, 1881. (No model.)

To all whom it may concern:

Be it known that I, GEORGE D. BANCROFT, of Boston, in the State of Massachusetts, have invented a new and useful Improvement in Electric Gas-Lighting Apparatus, of which the following is a specification.

The invention relates to an electrically-controlled mechanism for lighting and extinguishing gas, the principal feature of which is a thermo-spring acting at the temperature of the atmosphere in one direction to open the gas-cock, but when heated by the flame of the gas acting in the contrary direction to close the gas-cock, substantially as described in my Patent No. 205,032.

It sometimes happens that the gas is extinguished accidentally at one or more of the burners in a circuit before it is turned off throughout the circuit by the proper operation of the electro-mechanism, and when this is the case at any particular burner the thermo-spring at that burner, being no longer in the flame, becomes cool and will not act as it does when heated to close the gas-cock. At such burner, therefore, the gas continues to escape after it has been turned off at the other burners.

The object of this invention is to remedy this difficulty, and this I have accomplished by providing each thermo-spring with an additional spring and a catch, which act to store up a force created by the expansion of the thermo-spring while hot, and then exert said force upon the thermo-spring itself when it has become cool to move it sufficiently in the proper direction to close the gas-cock.

The apparatus to which I have applied the present invention, as shown in the drawings, differs slightly from the apparatus shown in my said Patent No. 205,032, since in the use of the apparatus now shown the gas is lighted by incandescence. A brief description, however, will be sufficient, for I have described and shown a burner with this slightly-modified apparatus, although without the present improvement, in Letters Patent to me No. 239,014 for a combined fire-alarm and gas-lighting apparatus.

Figure 1 is a front elevation of a gas-burner furnished with electrical apparatus embodying my invention, the gas-cock closed and the thermo-spring at the temperature of the at-

mosphere. Fig. 2 is a front elevation of the same, but with the gas-cock open and the thermo-spring at the temperature of the atmosphere, the gas having been accidentally extinguished without closing the cock. Fig. 3 is a side elevation of the apparatus in the condition shown at Fig. 2, the rod K, however, in section.

A is the burner; B, its cock, having at its forward end, outside of the burner, a segment-arm, C, by which it is turned. The cock B, between the burner and the segment-arm C, for a purpose to be described is cut away so that a cross-section of the part remaining is a sector of a circle, as shown at x.

D is an electro-magnet, in construction and mode of operation like the electro-magnet described and shown in my said Patent No. 239,014, being a cylindrical box of iron with a hollow core, around which is wound a wire. The core (not shown) is threaded at the upper end to receive the gas-burner, and at the lower end to screw upon the gas-pipe.

E is the armature, hinged to the box, as shown, and when the magnet is demagnetized kept up by a spring, s. The armature E has a large hole to permit the passage of the burner A and two small holes, through which pass two stiff heavy wires, w' w², which are united near the gas-tip by a platinum wire, p. The other ends of the wires w' w² are connected with the line, the coil of the electro-magnet being in the wire w'.

G is a thermo-spring, supported at one end by an arm, m, extending from the cylindrical box, and having its other end clamped in a block, f, sliding upon a rod, g, which, in turn, slides in a bracket, l, upon the cylindrical box, and which at its inner end is attached to a crank-pin, a, on the segment-arm C. The rod g is threaded and carries two adjustable nuts, n' n², limiting its motion in the bracket l, n³ n⁴ being two other nuts on said arm, for a purpose which will appear.

J is a spring coiled around one sleeve, t, and within a second sleeve, t', in the arm g, as shown. The sleeves are merely for the protection of the spring, which may be regarded as a spring coiled around the arm g with free ends, one pressing against the block f and the other against the nut n⁴. When the block f

moves on the arm *g* from the nut *n*³ it compresses the spring *J* against the nut *n*⁴, and if then the block *f* continues to move under the force of the thermo-spring the arm *g* is carried outward, moving with it the segment-arm *C*. If, after the spring *J* is compressed, the block *f* is held stationary in a manner which will hereinafter appear, and the arm *g* is allowed to move through the block *f*, the spring *J*, acting against the nut *n*⁴ under the resistance of the nut *n*³, will in turn carry the arm *g* outward and with the movement of the arm turn the segment-arm *C* outward. K is a rod loosely pivoted at one end to the segment-arm *C*, and having near its other or free end, upon the upper side, a cam-shaped projection, *e*, and upon the lower side a notch, *k*. The free end of the rod *K* rests upon the catch *x*, which in a certain position locks in the notch *k* of the rod *K*, while in all other positions it allows the rod *K* to slide over it in either direction. The segment-arm *C* has two shoulders, *c* and *c'*, and the armature *E* has a projection, *b*, against which one of the shoulders *c* or *c'* catches when the armature is lifted by the spring *s*. The armature carries also a yoke, *T*, an adjustable set-screw, *o*, in which reaches far enough down to strike the cam-projection *e* when the armature is in contact with its magnet. The pressure of the thermo-spring is inward at ordinary temperatures of the atmosphere, and outward when heated by the flame of the gas. In the normal condition of the apparatus the thermo-spring is cold, and the shoulder *c* of the segment-arm *C* rests upon the projection *b*. In this condition of the apparatus the cock is closed and the angle of the catch *x* points upward, the rod *K* resting lightly upon it. The operation is as follows: A single impulse sent through the line causes the magnet *D* to attract its armature *E*, and thereby releases the shoulder *c* from the projection *b*. The thermo-spring, being cold, and acting upon the nut *n*³ on the arm *g*, presses the segment-arm *C* inward, opening the gas-cock *B* and turning catch *x* to the position shown in Fig. 2. The wire *p* in the meantime is brought to a white-heat and lights the gas. The current is then broken, and the armature rising, the shoulder *c'* is caught upon the projection *b* and the cock kept open. The gas continuing to burn, the thermo-spring becomes heated, and, pressing outward, closes the spring *J* upon the nut *n*⁴ and draws the rod *K* outward until the notch *k* locks with the catch *x*, the locking

taking place just when the spring *J* is closed. If now the gas has continued to burn a second impulse sent over the line will release the shoulder *c'* from the projection *b*, and the thermo-spring, continuing to press outward, will carry the arm *g* still farther outward and turn off the gas; but if the gas has been accidentally extinguished any considerable length of time before the second impulse is sent over the line, the second impulse will then release the shoulder *c'* from the projection *b*, and now the thermo-spring, although cold, cannot press inward, since the notch *k* is locked upon the catch *x*. The arm *g*, however, is free to move through the block *f*, which is driven by the thermo-spring *G* against the nut *n*³, and the spring *J* accordingly, acting against the nut *n*⁴ under the resistance of the nut *n*³, carries the rod *g* outward and turns off the gas. It is obvious that the catch *x* and notch *k* must unlock when the arm *g* begins to move outward and to turn the gas-cock. In order, therefore, that the rod *K* may continue to furnish sufficient resistance to the thermo-spring for the operation just described, even if the spring *J* is sluggish in its movement, the set-screw *o* in the yoke *T* is adjustable to strike the upper part of the cam-projection *e* on the rod *K* at the moment the unlocking takes place, thereby binding or clamping the rod between the moving catch *x* and the set-screw *o*, and furnishing a resistance to the thermo-spring. The cam-projection *e* is cut away on the top, as shown, in order to let it pass freely under the set-screw when the armature is attracted to the electro-magnet for the purpose of disengaging shoulder *c* and engaging shoulder *c'* with the catch *b*.

I claim—

1. In an electrical gas-lighting apparatus, substantially as described, the combination of the catch *x*, notched rod *K*, and spring *J* with the gas-cock *B*, thermo-spring *G*, and arm *g*, for the purpose specified.

2. The burner and electric apparatus, substantially as described, in combination with the catch *x* upon the gas-cock, the yoke *T*, with its set-screw *o*, the segment-arm *C*, with shoulders *c* or *c'*, the thermo-spring *G*, the arm *g*, provided with proper stops or nuts, the spring *J*, rod *K*, notch *k*, and cam-projection *e*, for the purpose specified.

GEORGE D. BANCROFT.
